UNITED STATES PATENT OFFICE.

GEORGE P. CRAGIN, OF SPOKANE, WASHINGTON, ASSIGNOR TO IDA L. CRAGIN AND MAUDE S. McDONALD, OF SAME PLACE.

PASTE-BOTTLE.

SPECIFICATION forming part of Letters Patent No. 650,302, dated May 22, 1900.

Application filed February 8, 1900. Serial No. 4,534. (No model.)

To all whom it may concern:

Be it known that I, GEORGE P. CRAGIN, a citizen of the United States, residing at Spokane, in the county of Spokane and State of Washington, have invented new and useful Improvements in Paste-Bottles, of which the following is a specification.

My invention relates to that class of paste-bottles which embrace a central water-well 10 designed to receive and keep in a moist condition the brush to be used in the paste. It is designed more particularly as an improvement upon the bottle forming the subject-matter of my contemporary application filed 15 August 11, 1899, Serial No. 726,897; and it consists in the peculiar and advantageous construction hereinafter described, and particularly pointed out in the claims appended.

In the accompanying drawings, Figure 1 is 20 a diametrical section of my improved bottle with the cover thereon and the brush in its proper position in the central well. Fig. 2 is a horizontal section taken in the plane indicated by the broken line 2 2 of Fig. 1. Fig. 25 3 is a perspective view of the brush removed. Fig. 4 is a similar view of the cover. Fig. 5 is a similar view of the pitcher which is designed to be placed in the central well when the bottle is packed for shipment. Fig. 6 is 30 a detail diametrical section illustrating a modified construction of bottle. Fig. 7 is a perspective section illustrating a modified construction of well-holder. Fig. 8 is a similar view of another modified construction of 35 well-holder. Fig. 9 is a perspective view of a cylinder, of metal or other suitable material, which when cut on the broken lines and bent on the full lines indicated thereon produces two well-holders such as shown in Fig. 8. Fig. 10 is a perspective view of a well, of metal, 40 glass, or other suitable material, having a base-flange whereby the paste in the bottle is enabled to hold it in proper position therein. Fig. 11 is a similar view of another well having lateral feet or extensions at its base for 45 the same purpose as the flange of the well shown in Fig. 10.

Referring by letter to the said drawings, and more particularly to Figs. 1 to 5 thereof; 50 A is a bottle, which is preferably made in one piece of glass or other suitable material and

is circular in form, as illustrated. This bottle is provided at its upper edge with exterior screw-threads *a* and at its bottom has a lateral offset *b*, the upper wall of which forms 55 an abutment for a purpose presently pointed out.

B is a central water-well, which for the sake of cheapness and lightness is preferably formed of thin glass, and C is the well-holder, 60 The latter is formed in one piece of vulcanized rubber or other resilient material, and comprises a vertically-disposed socket *c*, which is preferably slightly smaller in diameter than the well B, so as to enable it to tightly 65 grip or embrace said well when the same is inserted, and lateral extensions or feet *d*, which extend radially from the lower end of the socket, as best shown in Fig. 2. The socket *c* of the holder may be bottomless, as shown 70 in Fig. 2, so as to enable the bottom of the well B to rest on the bottom of the bottle. This admits of the employment of a deep bottle and a brush having a portion below the cover, presently described, sufficiently long 75 to enable it to take up paste from the bottom of the bottle A when said bottle is almost depleted of paste. The feet *d* of the holder are of the proportional length illustrated, and hence it will be seen that when the well-holder 80 is pressed down into the bottle they will spring into the offset *b* thereof and assist in securing the socket *c* in the center of the bottle and against upward movement. When desired, the socket *c* of the holder C' may have a thin 85 bottom, as shown in Fig. 7, in order to afford a cushion for the bottom of the fragile water-well, calculated to prevent breakage of the bottom of said water-well incident to pressure thereon. 90

D is the cover of the bottle, which is preferably of light sheet metal and is provided with a central aperture *e* and a threaded marginal flange *f*.

E is a brush for applying the paste, and F 95 is an annular washer, of rubber or other suitable material, which is adapted, when the cover is moved down on the brush-handle and screwed on the bottle A, to be secured between the upper end of the well B and the 100 cover for a purpose presently described. The handle of the brush E is provided at about

its middle with two enlargements g h , between which the annular washer is interposed and held, as shown. The upper of these enlargements g is preferably tapered and of the proportional size shown, while the lower enlargement h is preferably of a similar size and shape.

By reason of the construction of the brush-handle as shown and described it will be observed that when the brush is placed in the water-well B with the washer F resting on the upper end of said well and the cover D is moved downwardly on the upper portion of the brush-handle and screwed on the bottle A the upper enlargement g of the handle will protrude through and snugly occupy the aperture e in the cover D and in conjunction with the washer F will seal the said aperture e , while the washer F will be compressed between the upper edge of the water-well and the cover, with the result that the water-well will be sealed by the washer and paste will be prevented from coming in contact with the under side of the cover around the aperture e , thus obviating the liability of paste being deposited on the brush-handle, and thereby reaching the fingers of the operator when the brush is used to apply paste. Again, it will be seen that in the event of the brush being improperly placed in the water-well, so that its handle rests against one side thereof, the wall of the aperture e will when the cover is moved down on the brush-handle and screwed on the bottle serve, in conjunction with the tapered enlargement g of said handle, to center the brush and cause the upper portion of the handle thereof to extend vertically above the cover and the enlargement g to snugly occupy the aperture e in the cover. It will further be observed that when applied in the manner stated the cover and rubber washer exert pressure on the upper end of the water-well, and thereby assist in holding said well in its proper position and prevent the escape of water therefrom no matter how violently the bottle is shaken or handled. The washer F on the brush-handle is also advantageous, since in the event of the brush being laid down it prevents the paste coming in contact with the support on which the brush is placed.

G (see Fig. 5) is a pitcher, of paper or other suitable light material. This pitcher is placed in the well B at the time of shipment, and when the bottle is to be placed in use is designed to be removed and used to fill or partially fill the well B with water.

In lieu of providing the bottle A with an offset b , the upper wall of which forms an abutment for the engagement of the feet of the well-holder C , I may provide it adjacent to its bottom with one or more (preferably four) ribs or abutments b' . These ribs are arranged a slight distance apart, so as to afford ways c' between them, and when the holder C is placed in the bottle the ends of its feet d are passed through ways, and the

holder is then given a partial turn to secure the feet below the ribs. It follows from this that when the construction of bottle shown in Fig. 6 is used the feet d of the bottle-holder need not be resilient.

In Fig. 8 of the drawings I have shown a modified well-holder C^2 , which is made of metal and comprises an annular socket c^2 , designed to receive the well B , inwardly-directed portions c^3 at the lower end of the socket designed to form a rest for the bottom of the well, and outwardly-directed feet c^4 , designed to rest on the bottom of the bottle and enable the paste therein to hold the holder against casual movement.

Two holders C^2 may be formed by cutting a metallic cylinder, such as shown in Fig. 9, on the broken lines and bending the metal on the full lines displayed in said figure, and hence the holders may be produced very cheaply.

In Fig. 10 I have illustrated a well B' , which may be of glass, metal, or other suitable material and is provided at its base with a lateral flange d^2 . The said flange is designed to rest on the bottom of the bottle, so as to enable the paste therein to hold the well against casual movement.

In Fig. 11 is shown a well B^2 , having lateral feet or flanges d^3 at its base, designed to serve the same purpose as the base flange d^2 of the well B' . When the well-holder C^2 , with the well B therein, or the wells B' B^2 are employed, the abutments b b' of the paste-bottle may obviously be dispensed with.

My improved paste-bottle is used in the ordinary manner—that is to say, the cover normally rests over the bottle and the brush stands in the well containing water, whereby it is kept soft and moist, as is desirable. When it is desired to apply paste to any article, the cover is screwed off the bottle and removed from the brush and said brush is used in the ordinary manner. Subsequent to using the brush it is replaced in the water-well and the cover is placed over the brush-handle and screwed down on the bottle, when the bottle may be tightly sealed and evaporation of the paste effectually prevented.

It will be appreciated from the foregoing that my improved paste-bottle is simple, compact, and light, the latter being due in large measure to the fact that the water-well is formed separately from the bottle A , and may therefore be formed of very light glass. It will also be appreciated from the foregoing that the paste in the bottle operates, in conjunction with the interior abutments thereof, to hold the well-holder and the well against casual movement.

Having thus described my invention, what I claim is—

1. The combination with a paste-bottle having threads at its upper edge, and a well in said bottle; of a cover having threads adapted to engage those of the bottle and also having an aperture arranged to coincide with the

- well, a brush having enlargements on its handle, the upper one of which is tapered and adapted to protrude through and snugly occupy the aperture of the cover, and an annular washer surrounding the brush-handle and interposed between the enlargements thereof; said washer being adapted to be compressed between the well and cover, substantially as specified.
10. 2. The combination with a paste-bottle having a well; of a cover adapted to be secured on said bottle and having an aperture arranged to coincide with the well, a brush having an enlargement on its handle adapted to protrude through and occupy the aperture of the cover, and an annular washer arranged on the handle below the enlargement thereof, substantially as and for the purpose described.
20. 3. The combination with a paste-bottle having an interior abutment adjacent to its bottom; of a well, and a removable holder therefor comprising a socket of resilient material adapted to grip the well, and an extension extending laterally from the base of said socket and adapted to engage the interior abutment of the bottle, substantially as specified.
4. The combination with a paste-bottle having a lateral offset at its bottom; of a well, and a removable holder therefor formed in one piece of resilient material and comprising a socket and feet extending laterally from the base thereof and adapted to spring into the lateral offset of the bottle, substantially as specified.
30. 5. The combination of a paste-bottle having threads at its upper edge and an interior abutment adjacent to its bottom, a well in said bottle adapted to receive a pitcher and also adapted to receive water, a removable holder for the well comprising a central socket and a lateral extension at the base thereof adapt-
- ed to engage the abutment of the bottle, a cover having threads adapted to engage those of the bottle and also having an aperture arranged to coincide with the well, a brush having enlargements on its handle, the upper one of which is tapered, and an annular washer surrounding the brush-handle and interposed between the enlargements thereof and adapted to be compressed between the well and cover, substantially as and for the purpose set forth.
15. 6. The combination with a paste-bottle having a water-well, and a removable cover; of a removable pitcher secured in the well by the cover; the said pitcher being adapted to be removed and used to fill the well with water, substantially as specified.
25. 7. The combination with a paste-bottle having threads at its upper edge, a well-holder in said bottle comprising a socket having inwardly-directed portions and outwardly-directed feet at its lower end resting on the bottom of the bottle, and a well arranged in the socket of said holder; of a cover having threads adapted to engage those of the bottle and also having an aperture arranged to coincide with the well, a brush having enlargements on its handle, the upper one of which is tapered and adapted to protrude through and snugly occupy the aperture of the cover, and an annular washer surrounding the brush-handle and interposed between the enlargements thereof; said washer being adapted to be compressed between the well and cover, substantially as specified.
35. In testimony whereof I have hereunto set my hand in presence of two subscribing witnesses.
